(57) **CLAIM**

The design for a lighting fixture, substantially, as shown and described.

DESCRIPTION

FIG. 1 is a lower perspective view of a lighting fixture of the present design.

FIG. 2 is an upper perspective view thereof.

FIG. 3 is a side elevational view thereof.

FIG. 4 is an opposite side elevational view thereof.

FIG. 5 is an end elevational view thereof.

FIG. 6 is an opposite end elevational view thereof.

FIG. 7 is a top plan view thereof.

FIG. 8 is a bottom plan view thereof.

FIG. 9 is a detailed view thereof as indicated in FIG. 1.

FIG. 10 is a detailed view thereof as indicated in FIG. 1.

FIG. 11 is a detailed view thereof as indicated in FIG. 2.

FIG. 12 is a detailed view thereof as indicated in FIG. 3.

FIG. 13 is a detailed view thereof as indicated in FIG. 3.

FIG. 14 is a detailed view thereof as indicated in FIG. 5.

FIG. 15 is a detailed view thereof as indicated in FIG. 5.

FIG. 16 is a detailed view thereof as indicated in FIG. 6.

FIG. 17 is a detailed view thereof as indicated in FIG. 7.

FIG. 18 is a detailed view thereof as indicated in FIG. 8; and,

FIG. 19 is a detailed view thereof as indicated in FIG. 8.

In FIGS. 1-4, 7, 8, portions of the design are broken by two pairs of break lines. The broken away symbols in the drawings indicate that the appearance of any portion of the article between each of the pairs of break lines forms no part of the claimed design.

1 Claim, 19 Drawing Sheets
